UNITED STATES PATENT OFFICE.

DEZSÖ SZALLA, OF NORTH TONAWANDA, NEW YORK.

AUTOMATICALLY-OPERATED GARAGE DOOR.

Application filed May 13, 1926. Serial No. 108,787.

This invention relates generally to garage construction and has more particular reference to a novel type of automatically operated garage door.

5 The invention has for an object the provision of an improved garage door construction which will open automatically upon the near approach of a vehicle, and automatically close upon exit of a vehicle from the garage.

For further comprehension of the invention, and of the objects and advantages thereof, reference will be had to the following description and appended claims in 15 which the various novel features of the invention are more particularly set forth.

Referring to the accompanying drawings forming a material part of this disclosure—

Fig. 1, is a front elevational view of a 20 garage constructed according to the invention.

Fig. 2, is a fragmentary vertical sectional view thereof, associated with an approaching vehicle.

25 Fig. 3, is a fragmentary vertical sectional view, taken on the line 3—3 of Fig. 6.

Fig. 4, is a fragmentary horizontal sectional view, taken on the line 4—4 of Fig. 3.

30 Fig. 5, is a fragmentary top elevational view with certain parts broken away disclosing certain other parts.

Fig. 6, is a fragmentary horizontal sectional view, taken on the line 6—6 of Fig. 2, but showing the door in open positions.

35 Fig. 7, is a vertical sectional rear view of the garage doors.

Fig. 8, is a fragmentary vertical sectional view, taken on the line 8—8 of Fig. 6.

40 Fig. 9, is an enlarged detail sectional view of the lower part of the door.

The reference numeral 10 indicates the ground level, being provided with a recess 10*, accommodating a platform 11, whose upper surface is flush with the ground level, 45 and a garage 12.

The vertical rods 13, 14, are journaled in supports 15, fastened to the front wall of the garage. The garage door is formed of a number of panels, 16, 17, 18, 19. The rods 13, 14, have rigidly fixed thereto supporting members 20, which are fastened to the outer edges of panels 16, 17, the inner edges of panels 16, 17 being hingeally connected, as indicated at 21, to the outer edges of panels 18, 19, while the inner edges of panels 18, 19 are provided with suitable casters 22

which engage rails 22' at the bottom and top edges of the door frame.

The springs 23 attached at one end to the garage walls, and at the other end to the panels 16, 17, normally urge the garage door to the opened position, shown in Fig. 6. Arms 24 are rigidly attached to the upper ends of the rods 13 and 14 and are pivotally and slidably connected at their ends to 65 arms or levers 25. The levers 25 are pivotally attached to the panels 18 and 19 and are adapted to move the latter from an open to a closed position when the rods 13 and 14 are rotated as hereinafter set forth.

Rigidly fixed to the lower end of rods 13, 14, are the segmental crank discs 26, 27 having catch notches 28, normally engaged by pivoted fingers 29, 30, depending from supports 31, and pressed into engagement 75 by expansion springs 32. Planks 33, 34 are depressibly mounted on springs 35, and normally have their upper faces flush with the ground level 10. A vehicle approaching the garage door soon presses downwards with its front wheels, the planks 33, 34, and pins 36, projecting from said planks abut against the pivoted fingers 29, 30 releasing the said fingers from the catch notches 28, and allowing the springs 23 to open the garage door. 80 It should be noticed that the position of the segmental crank disc 26, shown in Figs. 3 and 4 is that of the release, or door opened position. The vehicle may now enter the garage, and the vehicle operator may close 85 the garage door behind the vehicle.

Pivots connected to the segmental crank discs 26, 27, are the connecting rods 37, 38, connected at the outer ends to other connecting rods 39, 40, pivotally fastened to 90 the front of ears 41, 42, hingedly mounted at their rear ends to the platform 11, as indicated at 43. When the garage door is in the closed position the ears 41, 42 dispose substantially flush with the platform surface, shown in Figs. 2 and 5, while with the garage door in the opened position the ears are in a raised position, shown in Figs. 6 and 8. The platform 11 is provided with suitable slots 44 to allow the rods 39, 40 95 to assume a raised position, correspondingly with the ears. The vehicle upon being driven from the garage rides upon the ears 41, 42, depressing them, and causing the connecting rods to partially revolve the segmental crank discs, to a position in which the attached garage door is closed, and the 100 105 110

fingers 29, 30 engaged the notches in the said segmental crank discs, holding the doors closed against the opening action of springs 28.

5 While I have illustrated and described my invention, with some degree of particularity, I realize that in practice various alterations therein may be made. I therefore reserve the right and privilege of 10 changing the form of the details of construction or otherwise altering the arrangement of the correlated parts, without departing from the spirit or the scope of the appended claims.

15 Having thus described by invention, what I claim as new, and desire to secure by United States Letters Patent is:

1. In a device of the class described, a door, means for normally urging said door to an opened position comprising a spring attached at one end to said door and at the other end to a stationary member, means for latching said door to a closed position, comprising a segmental crank disc having a 25 catch notch and co-axially fixed to said door, a pivoted finger for engaging said catch notch, means for releasing said latching means upon the approach of a vehicle, and means for closing and relatching said door upon the departure of a vehicle.

2. In a device of the class described, a door, means for normally urging said door to an opened position comprising a spring attached at one end to said door and at the other end to a stationary member, means for latching said door to a closed position comprising a segmental crank disc having a catch notch and co-axially fixed to said door, a pivoted finger for engaging said catch notch, means for releasing said latching means upon the approach of a vehicle, comprising a compressible spring supported plank, and normally having its upper face flush with the ground level, a projecting pin on 45 said plank adapted to engage said pivoted finger, and means for closing and relatching said door upon the departure of a vehicle.

3. In a device of the class described, a door, means for normally urging said door to an opened position comprising a spring attached at one end to said door, and at the other end, to a stationary member, means for latching said door to a closed position, comprising a segmental crank disc having a 55 catch notch and co-axially fixed to said door, a pivoted finger for engaging said catch notch, means for releasing said latching means upon the approach of a vehicle comprising a compressible spring mounted plank normally having its upper face flush with the ground level, a projecting pin on said 60 plank adapted to engage, abutting said pivoted finger, and means for closing and

relatching said door upon the departure of a vehicle, comprising a rod pivotally connected to said segmental crank disc, another rod having one end connected to the outer end of first mentioned rod, and an ear journaled at its rear end to the ground level, and having its front end connected with the front end of said second mentioned rod.

4. In a device of the class described, pivotally mounted doors disposed in the entrance of a garage comprising hinged sections, a substantially vertical rod rotatively mounted 75 on the wall of said garage adjacent the entrance thereto, a lever rigidly secured to the upper end of said rod, a lever pivotally attached to said rigidly secured lever at one end and to said door sections at the other 80 adapted to guide said door sections during the opening operation thereof and to move said door sections to a closed position upon rotation of said rod, a plate secured on the lower end of said rod comprising an arcuate 85 edge portion having a notch therein, a pivotally mounted finger member adapted at one end to engage in said notch for holding said door in a closed position, and means comprising a trigger operable by the weight of an 90 approaching car adapted to disengage said finger from said notch for permitting said door to be opened.

5. In a device of the class described, pivotally mounted doors disposed in the entrance 95 of a garage comprising hinged sections, a substantially vertical rod rotatively mounted on the wall of said garage adjacent the entrance thereto, a lever rigidly secured to the upper end of said rod, a lever pivotally attached to said rigidly secured lever at one end and to said door sections at the other adapted to guide said door sections during the opening operation thereof and to move 100 said door sections to a closed position upon rotation of said rod, a spring attached at one end to said wall for normally urging said door to an open position, a plate secured on the lower end of said door comprising an arcuate edge portion having a notch therein, 105 a catch positioned below said door for engaging said notch means adapted to be actuated by the approach of a vehicle to disengage said catch from said notch for permitting said door to be opened by the action 110 of said spring, a lever pivotally mounted on said plate and extended substantially horizontally to a position in advance of the entrance of said garage, and a trigger pivotally attached to the end of said lever adapted 115 to be engaged by the wheels of a vehicle as the latter is driven out of said garage for rotating said rod to close the door.

In testimony whereof I have affixed my signature.

DEZSÖ SZALLA.
